UNITED STATES PATENT OFFICE.

STEPHEN MEAD, OF FORT BRANCH, INDIANA.

IMPROVEMENT IN APPLE-CORERS AND CUTTERS.

Specification forming part of Letters Patent No. 124,368, dated March 5, 1872; antedated March 4, 1872.

I, STEPHEN MEAD, of Fort Branch, Gibson county, Indiana, have invented an Improved Apple-Corer and Cutter, of which the following is a specification, in the drawing making part of which—

Figure 1 is a side elevation, and Fig. 2 a top view of the cutter.

This invention relates to a vertical tube having radial horizontal blades extending outward from its top, and said blades being inclosed within a ring concentric with said tube, in combination with an elastic arm, arranged for pressing apples down upon said tube and blades for the purpose of coring and quartering the same.

Referring to the drawing, *a* is the aforesaid vertical tube, the same being attached at its lower end to a foundation, *b*, through which is made a hole continuous with the bore of the tube *a*. The top of the tube has a cutting edge. The radial blades *c* have also cutting edges. The concentric ring *d*, to which the outer ends of the blades *c* are attached, strengthens

the same and prevents them from bending. Posts *e*, stepped in the foundation *b* at opposite sides of the ring *d*, support the latter. Upon the foundation *b*, near one end of the same, is block *f* secured, having a sloping top, to which the elastic arm *g* is fastened, through which a pin, *h*, is passed directly above the tube *a*. If an apple be stuck upon this pin, when the arm *g* is pressed down, the core is cut out and received within the tube *a*, whence it is voided through the orifice in the foundation *b*. At the same time the apple is quartered by the blades *c*.

I claim as my invention—

The combination of the tube *a*, blades *c*, ring *d*, posts *e*, elastic arm *g*, block *f*, and foundation *b*, as specified.

STEPHEN MEAD.
